DESIGN FOR A COCKTAIL SHAKER

Lurelle Guild, Noroton, Conn., assignor to Kensington, Incorporated, New Kensington, Pa., a corporation of Pennsylvania

Application April 20, 1935, Serial No. 56,481

Term of patent 3½ years

To all whom it may concern:

Be it known that I, Lurelle Guild, a citizen of the United States, residing at Noroton, in the county of Fairfield and State of Connecticut, have invented a new, original, and ornamental Design for a Cocktail Shaker, of which the following is a specification, reference being had to the accompanying drawing, forming a part thereof.

Fig. 1 is a side elevational view of a complete cocktail shaker embodying my new design, and

Fig. 2 is a similar view of the shaker with the top or cover removed. Fig. 3 is a side elevational view of the top or cover of the shaker from a direction substantially 90 degrees from that from which the view shown in Fig. 1 is taken. Fig. 4 is a top view of the cover or top of the shaker.

I claim:

The ornamental design for a cocktail shaker as shown and described.

LURELLE GUILD.
